UNITED STATES PATENT OFFICE.

BEN A. BALL, OF PAWTUCKET, RHODE ISLAND, ASSIGNOR TO AMERICAN TEXTILE COMPANY, INC., OF PAWTUCKET, RHODE ISLAND, A CORPORATION OF RHODE ISLAND.

DESIGN FOR LACE.

Application filed July 3, 1928. Serial No. 27,366. Term of patent 7 years.

To all whom it may concern:

Be it known that I, BEN A. BALL, a citizen of the United States, and a resident of Pawtucket, in the county of Providence and State of Rhode Island, have invented the new, original, and ornamental Design for Lace, of which the following is a specification.

Reference is had to the accompanying drawing, forming part thereof.

The figure is an elevation of lace, showing my new design.

I claim:

The ornamental design for lace, substantially as shown.

Signed at Pawtucket in the county of Providence and State of Rhode Island this 29th day of June A. D. 1928.

BEN A. BALL.
